PARTS TRAY FOR WORK STATION

Godfrey L. de Caccia, 4460 Overland, Culver City, Calif.

Filed Apr. 10, 1961, Ser. No. 64,710

Term of patent 14 years

(Cl. D58—13)

Fig. 3

Fig. 4

Fig. 5

FIG. 1 is a perspective view of a parts tray for a work station showing my new design;

FIG. 2 is a top plan view thereof on an enlarged scale;

FIG. 3 is a front elevation thereof;

FIG. 4 is a side elevation thereof; and

FIG. 5 is a bottom plan view thereof:

I claim:

The ornamental design for a parts tray for work station, as shown.
